UNITED STATES PATENT OFFICE.

AUGUST HUSSON, OF OSHKOSH, WISCONSIN, ASSIGNOR TO JOHN A. THOMPSON, OF CHICAGO,
ILLINOIS.

MINER'S LAMP.

No. 892,836.

Specification of Letters Patent.

Patented July 7, 1908.

Application filed February 17, 1908. Serial No. 416,245.

To all whom it may concern:

Be it known that I, AUGUST HUSSON, a citizen of the United States, and a resident of Oshkosh, in the county of Winnebago and State of Wisconsin, have invented a new and Improved Miner's Lamp, of which the following is a full, clear, and exact description.

This invention is an improvement in miners' lamps, residing particularly in the means employed in liquefying and volatilizing the fuel in order that it may freely pass by capillarity through the wick to the point of ignition. The fuel of miners' lamps is generally a mineral oil which becomes viscous or congeals at ordinary temperatures and accordingly requires artificial heat to thin it out sufficiently to pass up the wick. This heating means is usually a wire conductor extending from the flame down into the body of the lamp in the vicinity of the inner end of the wick-tube. As this wire becomes very hot it makes the oil immediately around it very thin and permits of the passage of the thin oil around the wire to the outside of the lamp body when the lamp is tilted forward. My invention contemplates the avoidance of this waste of fuel which obviously keeps the lamp in an unclean and greasy condition, which I do by making the conducting wire in two sections, one of the sections being fixed in, and closing, the inner end of the guide-tube arranged alongside the spout of the lamp, and the other section adjustable in this tube and adapted to project into the flame.

Reference is to be had to the accompanying drawings forming a part of this specification, in which similar characters of reference indicate corresponding parts in both views.

Figure 1 is a vertical central section through a miner's lamp embodying my invention; and Fig. 2 is a like sectional view on an enlarged scale through the wick tube, showing the adjustable section of the conducting wire, in dotted outline, when drawn outwardly to project in the flame, as when the lamp is in use.

The body or reservoir 5, of the lamp is of the usual construction having a hook 6, for supporting it, fixed to one side, and a conical spout 7 projecting upwardly and outwardly from the other side. Passing through the spout 7 from the body of the lamp is a conical wick-tube 8, of slightly less taper than the spout, which leaves an annular space be-

tween them for the reception of the fuel. A liquid-tight joint is formed between the spout at its outer end and the tube, which prevents any leak of the fuel thereabout.

The construction so far described is substantially old. My improvement specifically described consists in securing alongside the upper portion of the wick-tube, a guide-tube 9, in which there is placed a sectional wire conductor comprising an inner section 10 and an outer section 11, the inner section extending into, and closing, the inner end of the guide-tube and passing partially around the inner end of the wick-tube in substantial contact therewith, as best shown in Fig. 2, and the outer section is slidably received in this tube such that it may be drawn to the dotted position, as shown in Fig. 2, above the wick and into the flame, or, when the lamp is not in use, the slideable section of the wire may be pushed inwardly to a removed position, as shown in full lines. The lower portion of the guide-tube 9 is preferably expanded, as is also the lower end of the section 11 of the wire, as indicated at 12, which provides a stop, limiting the movement of this section of the wire when drawn outwardly. By this construction of the heating means for the fuel, it is apparent that the heat from the outer section of the wire when the wire is projected into the flame will be transmitted to the inner fixed section 10 through the conductivity of the tube 9, and also, a quantity of the heat will be transmitted directly from the tube 9 to the wick-tube, thus thinning the oil out sufficiently to pass up the wick by capillary attraction, the fuel being admitted to the wick not only through the inner end of the wick-tube but also through openings 13 in the walls of this tube, as is the customary practice. It will be seen that it will be impossible for the hot thin oil around the conducting wires to pass out of the guide-tube, as is the case where the wire slides in the tube and is made of a single piece, since the inner end of this tube is permanently closed by the inner section of the wire.

I am aware that it is old in lamps of this character to have conducting wires slide through tubes which pass to and through the fuel chamber. I, however, believe it to be broadly new to make the conducting wire in sections, the outer section being slideable and transmitting its heat to the inner section through the conductivity of a third member.

Having thus described my invention, I claim as new and desire to secure by Letters Patent:

1. The combination of a lamp body having a spout projecting upwardly and outwardly from the side thereof, a wick-tube extending from within the body through the spout and having a fluid-tight joint therewith, a guide-tube of conducting material arranged along side the wick-tube and extending into the body, and a wire conductor made in two sections, one of which is fixed in, and closes, the inner end of the guide-tube and extends adjacent to the inner end of the wick-tube, and the other adjustable in the guide-tube and adapted to project into the flame of the wick.
2. The combination of a lamp body having a wick-tube, a guide-tube of conducting material passing within the body, and a wire conductor made in two sections, the inner section of which is fixed to, and closes, the inner end of the guide-tube, and the other section slidably mounted in said tube, adapted to project into the flame of the wick.
3. The combination of a lamp body having a wick-tube, a guide-tube of conducting ma-

terial arranged alongside, and in contact with, the wick-tube, and a wire conductor made in two sections, one of which is fixed within, and closes, the inner end of the guide-tube and extending adjacent to the inner end of the wick-tube, and the other section slideable in the guide-tube and adapted to project into the flame of the wick.

4. The combination of a lamp body having a wick-tube, a guide-tube of conducting material having the inner portion thereof expanded, a wire conductor made in two sections, the inner section being fixed within, and closing, the inner end of the guide-tube, and the outer section slideable in the guide-tube, having an expanded portion within the expanded portion of the tube, said outer section being adapted to project into the flame of the wick.

In testimony whereof I have signed my name to this specification in the presence of two subscribing witnesses.

AUGUST HUSSON.
